UNITED STATES PATENT OFFICE.

WALTER A. SCHMIDT, OF PHILADELPHIA, PENNSYLVANIA, ASSIGNOR TO JOHN DUNLAP & SONS.

DESIGN FOR A CARPET.

SPECIFICATION forming part of Design No. 19,684, dated March 4, 1890.

Application filed February 5, 1890. Serial No. 339,349. Term of patent $3\frac{1}{2}$ years.

To all whom it may concern:

Be it known that I, WALTER A. SCHMIDT, of the city of Philadelphia, county of Philadelphia, State of Pennsylvania, have invented and produced a new and original Design for Carpets, of which the following is a specification.

The nature of my design is fully represented in the accompanying photographic illustration, to which reference is made.

I claim—

The design for carpets, as herein shown and described.

WALTER A. SCHMIDT.
